PORTABLE VIBRATOR

Austin T. Moore, 303 Saulda St., Columbia, S.C.

Filed Dec. 26, 1962, Ser. No. 72,945

Term of patent 14 years

(Cl. D83—1)

Fig. 1.

Fig. 2.

The undisclosed bottom portion is substantially flat except for the conventional motor housing as evidenced in broken lines in FIGURE 2.

The dominant features of my design reside in the full line portions shown on the drawing.

I claim:

The ornamental design for a portable vibrator, substantially as shown and described.
